UNITED STATES PATENT OFFICE.

GEORGE MURRAY WELKER, OF BRYAN, OHIO.

COMBINED SHELF AND TABLE.

SPECIFICATION forming part of Letters Patent No. 498,893, dated June 6, 1893.

Application filed June 28, 1892. Serial No. 438,294. (No model.)

To all whom it may concern:

Be it known that I, GEORGE MURRAY WELKER, a citizen of the United States, residing at Bryan, in the county of Williams and State 5 of Ohio, have invented certain new and useful Improvements in Display Shelves and Tables; and I do declare the following to be a full, clear, and exact description of the invention, such as will enable others skilled in the 10 art to which it appertains to make and use the same, reference being had to the accompanying drawings, and to the letters of reference marked thereon, which form a part of this specification.

15 My invention relates to a combined rack or shelf and table, and has for its object to so construct the parts that the device can be readily and quickly transformed from a rack or shelf into a table, or vice versa, and to 20 that end and for the accomplishment of such other objects as may hereinafter appear the invention consists in combining a series of cross bars or shelves with suitable hinged or pivoted side supports in such manner that 25 when said supports are in one position, for instance, an upright position, the cross bars or shelves will stand one above the other so as to afford a series of supports or shelves for articles that may be placed thereon and 30 when the pivoted supports are folded or turned down the cross bars or shelves shall be caused to assume a position wherein they will all lie in the same horizontal plane, or practically so, so as to form the leaf or flat 35 top of the table. The construction also admits of the device being used as a step ladder as for instance if the pivoted or hinged supports be turned sufficiently to place them in an inclined position instead of a vertical 40 or horizontal position the cross bars or shelves will stand at an inclination, that is in step order so as to constitute steps, or shelves inclined from top to bottom, there being employed suitable means for holding the shelves 45 or steps at the inclination desired.

The invention further consists in the construction and combination of parts herein- 50 after particularly described and then specifically defined by the claims, reference being had to the accompanying drawings forming part hereof.

Figure 1 is a perspective of the device

showing the shelves one above the other; Fig. 2 a vertical cross section through the device when adjusted for a table; Fig. 3 a vertical section of the device when the shelves are in an inclined position; Fig. 4 a rear view of a portion of the device, on an enlarged scale.

55 In the drawings the letter A designates a frame or stand of any approved pattern which is designed to support the shelves. To the upright portions B of the stand or frame there are pivoted the two opposite parallel bars C. To these parallel bars there are pivoted the forward portions of the shelves D, the rear portions of the shelves having a pivoted or hinged connection, for instance by means of the hinges E, with the rear parallel opposite bars F so that when the parallel bars C and F 60 are in an upright position the series of shelves 65 will stand one above the other in a horizontal position and when said parallel bars C and F are moved into a horizontal position the shelves will be caused to assume the same 70 horizontal plane with each other with their adjoining edges close together so as to form a flat top or leaf as illustrated in Fig. 3. The distance between the shelves when they are 75 one above the other will be equal to the width 80 of the shelves so as to bring the edges of the shelves close together when they are moved in the same horizontal plane, but it is obvious that the distance between the shelves may be greater than the width of the shelves; but it 85 is preferred to have the space between the shelves and the width of the shelves practically the same so that when the shelves are 90 in the same horizontal plane their edges will be close together and no material space left 95 between them. It is also preferred to set the rear parallel bars F a little inside of the front parallel bars C so that when the shelves are brought into the same horizontal plane the parallel bars F will lie just inside of the 100 parallel bars C as illustrated and the latter will lie between the former and sides of the stand whereby the stand will serve to brace the parts against lateral strain when the bars are in a horizontal position. It is preferred in practice to make one of the shelves, for instance the shelf D', stationary so that it will always stand in the same horizontal plane while the other shelves when folded will be

brought into the same plane therewith, the upper shelves being brought down to that plane and the lower shelves up to that plane.

- 5 A cross bar G extends across the upper portion of the stand or frame and besides serving to brace the same and to afford a stop for the pivotal bars when moved to an upright position also serves to afford a support for the parallel bars F when turned into 10 a horizontal position and serves also to check the movement of said bars and thus aid in sustaining the leaf or top in a horizontal position. The cross bar G may have notches or recesses H in which the parallel bars F may 15 lie when in their horizontal positions.

- Pins J and hooks I may be attached respectively to the upright portions B of the stand and to the parallel bars C so as to engage with each other and thus prevent the 20 top or leaf from accidentally tilting when in a horizontal position.

- The construction described enables me when desired to have a series of shelves one above the other for supporting articles of 25 merchandise, which shelves can be readily shifted to bring them into the same horizontal plane so that the goods or articles will be on the same plane when desired to be displayed along side of each other and to 30 be brought within more convenient reach of the salesman and purchaser. This change from the shelves one above the other to the top or leaf can be effected without removing the articles and without liability of the 35 articles slipping from off the shelves, as the shelves will always stand horizontally during the operation of shifting them from different horizontal planes into the same plane or vice versa. If the articles to be displayed be placed on the forward portions of the shelves they will not interfere with the bringing of the shelves into the same horizontal plane as in the adjustment of the shelves they are not brought near enough to 40 45 gether to practically lessen the space between the shelves until they have passed the point beyond where they would interfere with the articles or goods resting upon the shelf. If the goods or articles upon the shelves balance 50 each other above and below the point of pivoting the parallel side bars to the stand, the shelves will stand at any inclination between the vertical and a horizontal position in the same plane so that the goods can be displayed 55 at the angle or inclination desired. It is also obvious that by employing a hook and eye or

any other suitable holding device, the shelves can be held at the inclination desired to sustain them in step order so that if desired the device can be used as a step ladder for use in 60 the store room or elsewhere.

The device is composed of few parts, is simple in construction, is not liable to get out of repair, and is readily convertible from a shelf support into a table with a flat top. 65

I have described with particularity the details of construction and arrangement of the several parts but I do not mean to restrict myself thereto as it is obvious that many changes can be made and the essential features of my invention still be retained. 70

Having described my invention and set forth its merits, what I claim is—

1. The combination of the stand, pivotal bars sustained by said stand, shelves having 75 a loose connection with said pivotal bars to permit them to stand one above the other or in the same horizontal plane, and a transverse bar extending inwardly from the sides of the stand and in proximity to one set of pivotal 80 bars for the purpose of supporting said bars when in a horizontal position and affording a stop for them when raised to an upright position, substantially as and for the purposes described. 85

2. The combination of the stand, pivotal bars suspended by said stand, shelves having a loose connection with said pivotal bars to permit them to stand one above the other, or in the same horizontal plane, one set of said 90 bars standing inside of the other set to permit one set to lie along side of and between the other set and the sides of the stand when in a horizontal position whereby the sides of the stand will constitute a brace for said 95 parts, substantially as and for the purposes described.

3. The combination of the stand, the pivotal bars sustained by said stand, shelves having a loose connection with said pivotal bars 100 to permit them to stand one above the other at an inclination or in a horizontal plane, and a locking device for securing said shelves in both their horizontal and inclined positions, substantially as and for the purposes described. 105

In testimony whereof I affix my signature in presence of two witnesses.

GEORGE MURRAY WELKER.
